UNITED STATES PATENT OFFICE.

JOHN S. TOWNSEND, OF HARVEY, ILLINOIS, ASSIGNOR TO WHITING CORPORATION, OF HARVEY, ILLINOIS, A CORPORATION OF ILLINOIS.

ELECTRIC SAFETY LIMIT SWITCH.

Application filed November 15, 1920. Serial No. 424,129.

This invention is a safety limit switch for use in efficiently stopping any mechanism moved at high speed by electrically propelled apparatus. While its application 5 may be very general to devices having the same sort of mechanism the invention was primarily made for use in connection with electric traveling cranes and will therefore be described in connection with such mechanism.

It is well understood in the art that in a building equipped with a traveling crane, movable horizontally at a certain given height, the effective useful part of the capacity of the building is the part located 15 below the highest point to which the lowest part of the hook or other moving part of the crane can be safely elevated. For this reason crane builders always strive to so 20 construct the device that the hook and attached parts can be moved to the highest point of safety in the building. It is also well understood that in the use of a high speed crane when the hook is elevated at 25 high speed and the power is shut off the hook must necessarily travel a considerable distance upward before the brakes, or other stopping devices, act effectively, while on the other hand, a slow moving hook might 30 be safely stopped at a considerably higher point without danger to the crane mechanism. The object of this invention is to provide an automatic mechanism which will cut off the current, controlling the hook, at a 35 point consistent with high speed operation of the machine and to provide a manually controlled mechanism, by which, only under the operator's constant personal control the power may be thrown in again, in order to 40 permit further elevation of the hook and attached parts, up to another predetermined point beyond which the current is absolutely thrown off and kept off so that the hook 45 cannot by any possibility proceed further, and thus damage the crane mechanism.

The invention consists in mechanism for attaining the foregoing objects which can be comparatively easily constructed and applied to mechanism requiring it, which is 50 perfectly positive and efficient in operation and is not liable to get out of order. More particularly the invention consists in features and details of construction which will be more fully set forth in the specification 55 and claims.

Referring to the drawings in which like numerals designate the same parts throughout the several views:—

Figure 1 is a diagrammatic view of mechanism illustrating this invention in its preferred form.

Figure 2 is a side view of a crane, and end view of a trolley, partially in section, illustrating one form of the mechanism of this invention in actual application.

Figure 3 is an end view taken of the right of Figure 2, certain parts being cut away.

Figure 4 is an end view of the switch mechanism which is shown diagrammatically in Figure 1.

Figure 5 is a side view of the mechanism of Figure 4, certain parts being shown in section.

Figure 6 is a sectional view thru approximately the center of Figure 4, but in place 75 of that part of the mechanism which is seen on looking at Figure 4 it shows a modified construction of the switch mechanism which is used in the device of Figures 2 and 3.

Figure 7 is an end view taken on line 7—7 of Figure 6 showing mechanism common to the structures of both Figures 5 and 6.

In Figure 1 the winding drum 10 is shown, diagrammatically, connected by 85 gearing 12 to the motor shaft 14 driven by a conventional form of electric motor 16, provided with suitable wiring 18 of conventional form leading to a controller mechanism 20 provided with the usual conventional resistance 21 and in the case here illustrated suitably connected up to a pair of normally open switches commonly called a contactor 22 and a single manually operated switch 24 all of conventional form installed to be operated as hereinafter described.

The contactor 22 is movable from the normally open position shown in Figure 1 against the action of spring 22^a to closed 100 position across the adjacent opposite contacts 23 whenever current is sent thru an energizing coil 26 of conventional form. In this particular standard diagram shown alternating current is used and it is 105 applied to the device from a suitable source at the points 28. In the physical mechanism applied to a traveling crane, insulators 30 are applied at the end of the crane bridge and that part of the wiring mechanism at 110

the left of the insulators is applied to and carried by the crane bridge in conventional manner, whereas the other parts of the wiring system are located at some other convenient point, usually at the operating station, on the crane bridge.

In connection with the foregoing conventional mechanism a special stop and switch mechanism is applied for operation by the crane hook block 32, which is conventionally suspended from the drum 10 by a hoisting rope 34. In the case illustrated in Figure 1, block 32 does the mechanical portion of the stopping by engaging a transversely disposed rope 36, passing as shown between the ropes 34, so that the block cannot fail, in its upward travel, regardless of its lateral swinging movement, to engage this rope 36. One end of the rope is fastened to a fixed support 38, while the opposite end portion of the rope, after passing over suitable pulley 40, is wound around and finally secured at one point on the circumference of a wheel 42, carried by shaft 46 suitably mounted to 15 drive pinion 48, which in turn, thru a gear 50 actuates shaft 52. A spring 44 connected to hub 45 and to a fixed support 47, is adapted to move the wheel and attached parts contrary to the pull of rope 36. 20 Mounted on this shaft 52 which is common to both of the switch mechanisms heretofore referred to, are two parallel segmental pulleys 54 and 56. The pulleys 54 and 56 are conventionally insulated from shaft 52 but 25 their hubs are in mechanical and electrical contact with each other, being held in such contact by the nut 57 on the end of the shaft (Figures 5 and 6). The circumferential portion of pulley 54 is comparatively 30 short so that it is only during a comparatively short portion of the arc of travel of shaft 52 that an adjacent contact member 60 is in engagement with this surface 58. On the other hand, pulley 56 is provided with a 35 circumferential surface 62 of relatively much longer length so that when adjacent contact members 64 are in engagement with it they remain in such engagement or contact during a much longer portion of the arc of travel of shaft 52. Both pulleys 54 and 56 40 are so positioned and arranged that there is a substantial portion of the arc of travel of shaft 52 during which there is no contact with the adjacent switch points on either 45 one of these pulleys. Contact 60 is so connected into the wiring circuit 18 thru a wire 66 that whenever block 32 strikes rope 36 and thus ultimately rotates shaft 52 to the point where surface 58 of pulley 54 is disengaged from contact 60, magnet 26 is deenergized thus allowing the spring 22^a to open connector 22 and thus throw off the current from motor 16 and stop the powerful elevation of the hook block 32.

65 Switch 24 is so connected in the circuit

that when it is manually closed, magnet 26 is operated, even tho members 58 and 60 may be in contact to close connector 22 to restore or maintain as the case may be, the passage of electric current to the motor 16 to operate the drum 10 and that this condition will continue as long as switch 24 remains closed, except as hereafter provided.

The relatively long circumferential contact surface 62 is so positioned and connected into the circuit, thru wire 70 leading from contact 64 that switch 24 can operate as described in the last sentence so long as members 64 remain in engagement with surface 62 but that when block 32 moves rope 36 upward sufficiently so that shaft 52 rotates far enough to move contacts 64 off from contact surface 62, the circuit which switch 24 controls is in fact broken with the result that the operator holding switch 24 closed is no longer effective and contactor 22 automatically opens as heretofore described, thus permanently preventing any further upward movement of the hook 32 under the power of motor 16.

In actual practice the pulleys 54 and 56 are so proportioned and positioned that when block 32 engages rope 36 it causes the breaking or opening of contact 58-60 at a point or time in the upward travel of block 32 where if it is moving at high speed it has sufficient space within which to travel upward so that the brake and other mechanism can stop it before it actually engages and thereby injures the crane mechanism and that if the operator maintains his hold on switch 24 the contact at 62-64 will not be broken as described until the hook block 32 has traveled as near to the crane mechanism as it can possibly go with safety at 105 any speed, beyond which it cannot be moved further. In actual practice the operator is not supposed to close switch 24 when the crane is working at high speed until the block 32 has been automatically stopped by 110 breaking contact mechanism 58-60 and he thereafter sees that the momentum upward of the block is not going to carry it high enough. On the other hand, if the crane is working very slowly he may close switch 115 24 at or before the time contact 58-60 is broken and maintain it until switch 62-64 opens. This does away with the temptation, not to say necessity, of operators of ordinary cranes having only a safety limit switch at the level at which switch 58-60 operates to run the load up at high speed in order to make it carry up by momentum to the upper limit of travel, viz.: with this invention the operator can operate slowly all 120 the way up and be sure of getting the load up to the maximum point without subjecting the crane mechanism and the load to the risks which occur in high speed operation, even under the most safe provisions. 125 130

When block 32 moves rope 36 upward to manipulate the mechanism as described, the pull of rope 36 compresses spring 44 which returns the parts to normal position just as soon as the crane operator manipulates the device to cause block 32 to start to descend.

The controller mechanism 20 is of absolutely standard conventional form and the switch devices herein provided are only connected into it on its side which is used in the load elevating operation. Its side which is used in the lowering operation is not connected to these switches so that whenever the operator manipulates the standard mechanism under his control to lower the hook block 32 he can do so regardless of the positions of the various switch devices entering into this invention as described.

In the modified form of construction shown in Figures 2, 3 and 6 the spring 44 is dispensed with and its place is taken by a rope and weight mechanism. In this modified construction the wheel 42 will be designated as 72. To a suitable point in its circumference a rope 74 is secured intermediate of its ends so that it has one free end carrying a relatively small weight 76 and its other end carrying a relatively large weight 78, which the rope reaches after passing over suitably disposed pulleys 80. Weight 78 is perforated or otherwise provided with guides thru which ropes 34 pass to insure the weight 78 following the swinging movement of block 32. In the construction of Figures 2 and 3 weight 78 is enough heavier than weight 76 so that when both weights have control of the pulley, weight 78 predominates and thereby holds the switch mechanism in the position of Figure 1, that is to say in the same position, against stop mechanism 82 in which the parts are held by spring 44. When, however, block device 32 ascends far enough to engage and lift weight 78, weight 76 is thrown in control with the result that it moves the parts in the same manner in which they are moved in the other construction when block 32 moves upward and pulls on rope 36.

This weight mechanism form of device has the advantage of doing away with the spring and thus avoiding what might happen if the spring broke or otherwise failed to operate.

It hardly seems necessary to describe the conventional form of crane shown in which the main crane girder 86 carrying the wheels 88 on which the trolley 90 bearing the crane mechanism described travels in the ordinary manner. The main operating switch devices described are enclosed in a conventional form of box 92 mounted on the trolley in convenient position for operation.

Having thus described my invention what I claim as new and desire to secure by Letters Patent is:-

1. In a power mechanism, a moving mem-

ber, power means propelling it, two power cut off devices, automatically operatable in succession by the moving member to, provided the power is on, cut it off and normally inoperative mechanism, rendered operative by constant manual holding, in connection with the second cut off mechanism, adapted while so manually operated to restore the power to the propelling mechanism from the time the first cut off operates until the second cut off itself operates.

2. In a power mechanism, a moving member, electrically-operated means propelling it, two power cut off devices, automatically operatable in succession by the moving member to, provided the power is on, cut it off and normally inoperative mechanism rendered operable by constant manual holding, in connection with the second cut off mechanism, adapted while so manually operated to restore the power to the propelling mechanism from the time the first cut off operates until the second cut off itself operates.

3. In a power mechanism, a moving member, power means propelling it, two power cut off devices automatically operatable in succession by the moving member to, provided the power is on, cut it off and normally inoperative mechanism rendered operative by constant manual holding, in connection with the second cut off mechanism, adapted while so manually operated to restore the power to the propelling mechanism from the time the first cut off operates until the second cut off itself operates.

4. In a power mechanism, a moving member, electrically operated, means propelling it, two power cut off devices automatically operatable in succession by the moving member to, provided the power is on, cut it off and normally inoperative mechanism rendered operative by constant manual holding, in connection with the second cut off mechanism, adapted while so manually operated to restore the power to the propelling mechanism from the time the first cut off operates until the second cut off itself operates.

5. In mechanism of the class described, a movable member, electrically operated mechanism for propelling the moving member, an automatic switch, operated by the moving member at a predetermined point in its travel to cut off the current from the operating mechanism, a normally open switch closable by constant manual holding, adapted when so closed to restore said current, and means operable at a more distant point in the travel of the moving member finally cutting off the current.

6. In a device of the kind described, a moving member, an electric circuited power mechanism normally moving said member, a shaft, means by which the moving member partially rotates the shaft, a pair of par-

allel segmental contact members, of different circumferential lengths, on the shaft, a contactor in the electric circuit adapted to control the power, a contact member opposite the shorter segmental contact adapted when disengaged from the segment to cause the contactor to shut off the power, a manually operated switch in a circuit arranged to restore the power so shut off and contact members, engageable with the longer segmental contact on the shaft, so connected into the last mentioned circuit that so long as the segment remains in position to maintain such contact, and said manually operated switch is operated, the effect of said switch action operated by the shorter segment is negated.

7. In mechanism of the class described, a moving load controlled member, an electric circuited power mechanism normally moving said controlled member, a movable switch member, means by which at a predetermined time in the travel of said controlled member it moves the switch member, a pair of separated, parallel circuit-completing members of different operating lengths on the switch member, a contactor in the electric circuit adapted to control the power, a cooperating member opposite the shorter circuit-completing member on the switch member adapted when disengaged therefrom to permit the contactor to shut off the power, a circuit arranged to restore the power so shut off and another cooperating member cooperating with the longer of said circuit completing members on the switch member, so connected into the last mentioned circuit that so long as the longer circuit-completing member remains in position to maintain said circuit closed, the effect of the power shut off by the shorter circuit-completing member is negated.

8. In mechanism of the class described, a moving load controlled member, an electric circuited power mechanism normally moving said controlled member, a movable switch member, means by which at a predetermined time in the travel of said controlled member, it moves the switch member, a pair of separated, parallel circuit-completing members of different operating lengths on the switch member, a contactor in the electric circuit adapted to control the power, a cooperating member opposite the shorter circuit-completing member on the switch member adapted when disengaged therefrom to permit the contactor to shut off the power, a manually controlled switch in a circuit arranged to restore the power so shut off and another cooperating member cooperating with the longer of said circuit-completing members on the switch member, so connected into the last mentioned circuit that so long as the longer circuit-completing member remains in position to maintain said

circuit closed and said switch is operated, the effect of the power shut off by the shorter circuit-completing member is negated.

9. In mechanism of the class described, a moving load controlled member, an electric circuited power mechanism normally moving said controlled member, a movable switch member, means by which at a predetermined time in the travel of said controlled member it moves the switch member, a pair of separated, parallel circuit-completing members of different operating lengths on the switch member, a contactor in the electric circuit adapted to control the power, a cooperating member opposite the shorter circuit-completing member on the switch member adapted when disengaged therefrom to permit the contactor to shut off the power, a circuit arranged to restore the power so shut off and another cooperating member cooperating with the longer of said circuit-completing members on the switch member, so connected into the last mentioned circuit that so long as the longer circuit-completing member remains in position to maintain said circuit closed, the effect of the power shut off by the shorter circuit-completing member is negated, and means resisting said movement of the switch member, returning said switch to original position when the controlled member moves in the opposite direction.

10. In mechanism of the class described, a moving load controlled member, an electric circuited power mechanism normally moving said controlled member, a movable switch member, means by which at a predetermined time in the travel of said controlled member, it moves the switch member, a pair of separated, parallel circuit-completing members of different operating lengths on the switch member, a contactor in the electric circuit adapted to control the power, a cooperating member opposite the shorter circuit-completing member on the switch member adapted when disengaged therefrom to permit the contactor to shut off the power, a manually controlled switch in a circuit arranged to restore the power so shut off and another cooperating member cooperating with the longer of said circuit-completing members on the switch member, so connected into the last mentioned circuit that so long as the longer circuit-completing member remains in position to maintain said circuit closed and said switch is operated, the effect of the power shut off by the shorter circuit-completing member is negated, and means resisting said movement of the switch member, returning said switch to original position when controlled member moves in the opposite direction.

11. In mechanism of the class described, a movable switch member, means automati-

5 cally restoring said switch to initial position, a pair of separated, circuit-completing members of different lengths carried by the switch member, stationary cooperating members opposite said circuit-completing members adapted when the switch is moved to open circuits in which they are respectively included during periods of time determined by the lengths of the respective circuit completing devices on the movable switch.

10 12. In mechanism of the class described, a rotatable switch member, means automatically restoring said switch to initial posi-

tion, a pair of separated, circuit-completing members of different lengths carried by the 15 switch member, and stationary cooperating members opposite said circuit-completing members adapted when the switch is moved to open circuits in which they are respectively included during periods of time determined by the lengths of the respective 20 circuit completing devices on the movable switch.

In witness whereof, I have hereunto subscribed my name.

JOHN S. TOWNSEND.
